UNITED STATES PATENT OFFICE

132,715

DESIGN FOR A FLOOR BRUSH ATTACHMENT FOR SUCTION TOOLS

Dewey M. Dow, Toledo, Ohio, assignor to Air-Way Electric Appliance Corporation, Toledo, Ohio, a corporation of Delaware

Application September 27, 1941, Serial No. 103,540

Term of patent 14 years

To all whom it may concern:

Be it known that I, Dewey M. Dow, a citizen of the United States, residing at Toledo, in the county of Lucas and State of Ohio, have invented a new, original, and ornamental Design for a Floor Brush Attachment for Suction Tools, of which the following is a specification, reference being had to the accompanying drawing, forming part thereof.

Fig. 1 is an inverted plan view of a floor brush

attachment for suction tools embodying my new design.

Fig. 2 is a front elevation of the same.

Fig. 3 is a side elevation of the same.

I claim:

The ornamental design for a floor brush attachment for suction tools, as shown.

D. M. DOW.
